UNITED STATES PATENT OFFICE.

JOHN F. SCOTT, OF EVANSVILLE, INDIANA, AND THOMAS M. GALLAGHER,
OF ST. LOUIS, MISSOURI.

BRAKE-BEAM.

SPECIFICATION forming part of Letters Patent No. 741,380, dated October 13, 1903.

Application filed March 2, 1903. Serial No. 145,629. (No model.)

To all whom it may concern:

Be it known that we, JOHN F. SCOTT, residing at Evansville, in the county of Vanderburgh and State of Indiana, and THOMAS M. GALLAGHER, residing in the city of St. Louis, in the State of Missouri, citizens of the United States, have invented certain new and useful Improvements in Brake-Beams, of which the following is a full, clear, and exact description, reference being had to the accompanying drawings, forming part of this specification.

Our invention relates to an improved brake-beam for railway-cars; and it consists in features of novelty hereinafter fully described, and pointed out in the claims.

Figure I is a perspective view of our improved beam. Fig. II is an enlarged transverse section taken on line II II, Fig. I. Fig. III is an enlarged transverse section taken on line III III, Fig. I. Fig. IV is a detail longitudinal section taken on line IV IV, Fig. III. Fig. V is a detail top view, part in section, showing one end of the beam with the brake-head removed. Fig. VI is a vertical section, on a reduced scale, taken on line VI VI, Fig. V.

Referring to the drawings, 1 represents the body of the beam, preferably made of cast-steel and which has a base 2 and a flange 3.

4 represents the brake-heads. They are slipped onto the ends of the beam and held in place by pins 5.

6 is a fulcrum. It is provided with a shank

7, fitting in a socket 8, formed in the center of the beam. The beam has a swell 9 to add strength at the point where the socket is located. The fulcrum is held to the beam by a pin 10, that passes through the beam and through the shank 7.

11 represents the guard-fingers. They fit in sockets 12, formed in the beam, and are held therein by pins 13. The beam has swells 14 to add strength at the point where the sockets 12 are located.

By thus constructing a brake-beam the brake-heads, fulcrum, and guard-fingers can all be attached and renewed without the use of tools and by any inexperienced person.

We claim as our invention—

1. A brake-beam having sockets to receive the fulcrum and guard-fingers, the fulcrum and guard-fingers being adapted to be held in place by pins passing therethrough and through the beam, substantially as set forth.

2. A brake-beam having brake-heads slipped thereon and held thereto by means of pins, and fulcrum and guard-fingers fitting in sockets formed in the beam and held therein by means of pins, substantially as set forth.

JOHN F. SCOTT.

THOMAS M. GALLAGHER.

In presence of—

E. S. KNIGHT,

N. V. ALEXANDER.
